FIRE HOOK

Curtis E. McGhee, Washington, D. C.

Application April 16, 1935, Serial No. 16,702

1 Claim. (Cl. 7—17)

This invention relates to improvements in fire hooks such as is used by firefighters to tear away a portion of the ceiling of a room to determine whether the fire is passing between the ceiling 5 and the floor of the room above.

In the removing of the portion of the ceiling the hook is forced through the ceiling, turned so as not to come back out and pulled to remove a portion of the ceiling. Ceilings are sometimes 10 made with a lining of heavy tin or expanded metal, and with the usual type of hook, which consists of a spear head and a slightly curved hook which extends horizontally from the spear head at a point about 5 to 9 inches below the 15 point of the spear, it was necessary in most ceilings to puncture a row of holes in the ceiling with the spear before it was possible to force the hook through the said ceiling. The room where such 20 a hook is used is usually smoky and hot and the time consumed for such operations is considerable.

One object of my invention is to make a fire or ceiling hook in which the hook part may be more effectively and easily passed through the 25 ceiling and which will enable one to tear away a portion of the ceiling more quickly and efficiently.

Other advantages will be at once apparent to those familiar with the use of firefighting tools.

A preferred form of my invention is illustrated 30 in the drawing, wherein Figure 1 is a side elevation of my improved hook, Figure 2 is an end elevation of a portion of the same and Figure 3 is a section on line 3—3 of Figure 1.

The hook consists of a handle, 1, on which is 35 attached a metal head, 2. The head consists of a socket, 3, by which it is attached to the handle, a triangular portion, 4, and a pointed portion 5. One side, 6, of said triangular portion is on a line with the handle, one side, 7, extends at right 40 angles to the side 6 and turns downward slightly at the end to form a hook. The third side, 8, of the triangular portion extends between the tip of the hook and the pointed portion of the head. The pointed portion, 5, preferably extends be-

yond the point made by the intersection of the sides 6 and 8 though this is by no means necessary. The side 8 is beveled as shown by Figure 3 so as to form a cutting edge. The side 7 is not sharpened in any way and is curved very little except at the very tip so that a maximum of surface is supplied whereby the hook cannot be removed without bringing a portion of the ceiling with it. 5

In the preferred form the hook portion extends 10 laterally approximately 3—6 inches and the distance between the tip of the point and the inside of the hook portion is from 4—8 inches, preferably 6 inches, this length furnishing a comparatively long triangular portion which is easy to 15 force through the ceiling and at the same time this is not so long that the floor above the ceiling will interfere or be damaged.

Numerous variations and modifications may be 20 made without departing from the spirit of the invention. For example, instead of a solid metal head there may be merely a point and a hook with a separate piece of metal extending between the two.

Having now fully explained the invention, I 25 claim:

A fireman's hook comprising a handle, having a flat metal substantially triangular head at one end thereof, one side of the head being substantially in alignment with the side of the handle, 30 the opposite side of the head extending laterally of the handle and terminating at its lower end in a hook portion, the underside of the hook portion being blunt and slightly curved, a pointed portion 35 extending beyond the triangular metal head, one side of the pointed portion being substantially in alignment with the first mentioned side of the head, the other side of the pointed portion being inclined at an angle to the second mentioned side of the head, the head having a sharpened edge extending between the tip of the hook and the base of the pointed portion. 40

CURTIS E. McGHEE.
